UNITED STATES PATENT OFFICE.

CHARLES A. LINDSTROM, OF EAST RUTHERFORD, NEW JERSEY, ASSIGNOR
OF TWO-THIRDS TO ARTHUR C. VAN RODEN AND GARRET VAN WAG-
ONER, OF EAST RUTHERFORD, NEW JERSEY.

NON-REFILLABLE BOTTLE.

SPECIFICATION forming part of Letters Patent No. 730,380, dated June 9, 1903.

Application filed March 18, 1903. Serial No. 148,410. (No model.)

To all whom it may concern:

Be it known that I, CHARLES A. LINDSTROM, a citizen of the United States, residing at East Rutherford, in the county of Bergen and State 5 of New Jersey, have invented a new and useful Non-Refillable Bottle, of which the following is a specification.

My invention relates to non-refillable bottles, and has for its objects to produce a detail 10 vice of this character which is comparatively simple of construction, one which may be applied to bottles with merely nominal increase in the cost of the latter, and one which in operation will efficiently prevent the refilling of the bottle after its contents have been once discharged, thus obviating the fraudulent substitution of an inferior grade of goods.

To these ends the invention comprises the novel details of construction and combination 20 of parts more fully hereinafter described.

In the accompanying drawings, Figure 1 is a vertical transverse section illustrating my invention as applied to a bottle, the parts being in the normal position. Fig. 2 is a similar view illustrating the parts in the discharging position. Fig. 3 is a detailed view of the retaining-disk. Fig. 4 is a detailed horizontal section on the line 4 4 of Fig. 1.

Referring to the drawings, 1 indicates a bottle composed of glass or other suitable material and having a neck 2, which has formed near its lower end upon its interior a horizontal flange or shoulder 3, while a similar shoulder 4 is formed adjacent to the longitudinal center of the neck. In applying my invention I mount within the neck a cylindrical shell or sleeve 5, preferably of cork. This sleeve bears at its lower end upon the lower flange 3, and is provided with a central annular opening 6, which receives a longitudinally-movable valve body or stem 7, provided with a disk-like head 8, which has its side face downwardly and inwardly beveled; as at 9. The valve-body portion 7 has formed at its lower end an elongated slot 11, which has parallel inner side faces and curved inner end faces. 12 is a weight or tumbler which is recessed to receive the lower end of the body portion 7 and is connected thereto by means

of a horizontal annular pintle 13, which is inserted through the slot 11 and suitable perforated ears formed on the upper end of the tumbler. These parts are all preferably composed of glass, but may, of course, be formed from any other suitable or desired material. 50 55

14 indicates a disk-like retaining member which is seated upon the upper flange 4 and within the bottle-neck. This member, which occupies a position just above the valve-head 8, is provided with a central discharge-opening 15 and has its horizontal upper and lower faces grooved or corrugated, as at 16.

17 indicates a cup-shaped member which is seated within the upper end of the bottle-neck and bears at its lower end upon the upper face 60 of the retaining member 14, and has formed at its upper end a horizontal outwardly-projecting peripheral flange 18, which when the thimble is in place seats upon the upper edge of the bottle-neck. The member 17 has 70 a horizontal bottom portion 19, which is perforated at its point of juncture with the side walls of the member by means of a series of downwardly and outwardly diagonally disposed perforations 20, which at their lower 75 ends seat directly over the corrugations 16, formed on the upper face of the retaining member 14.

In practice the weight 12 will, when the bottle is in its normal position, or, in fact, in 80 85 90 95 except its discharging position, serve to draw the body portion 7 of the valve downward to thus press the beveled face 9 of the valve-head 8 tightly against the upper end of the sleeve 5 and prevent the ingress or egress of liquid to or from the bottle. In this connection it is to be noted that when in normal position the weight by its gravity alone holds the valve to its seat and that when the bottle is tilted the upper peripheral edge of the weight engages beneath the edge of the sleeve 5, thus positively holding the valve against longitudinal movement. When, however, the bottle is inverted to bring it to a discharging position, the body portion of the valve will be relieved of the weight of the tumbler and will slide longitudinally to move the valve-head away from its seat upon the

sleeve 5, thus permitting the free discharge of the liquid, which after it passes the valve flows through the central opening 15 of the member 14 and through the passages formed 5 by the corrugations 16 between the upper face of the member 14 and the bottom 19 of member 17, and thence outward through the diagonally-disposed perforations 20.

In assembling the parts I first insert the 10 body 7 of the valve into the sleeve 5 and attach the tumbler to the lower end of the valve-body in the manner above explained. I then place the sleeve and valve into the neck of the bottle and mount the retaining 15 member 14 in proper position upon its flange over the same, then insert the cup-shaped member 17, the outer surface of which I previously coat with a thin layer of cement. The device is now ready for use and the cup-shaped member 17 is adapted to receive the 20 usual cork or stopple 21.

From the foregoing it will be seen that the device is of simple construction and will in practice efficiently perform its functions, and 25 that owing to the peculiar relative disposition of the various openings through which the liquid is discharged the insertion of a wire or other instrument for tampering with the valve is entirely obviated.

30 It is to be understood that I do not limit or confine myself to the precise details herein

shown and described, inasmuch as minor changes may be made in the form, proportions, and manner of assemblage of the parts without departing from the spirit of my invention. 35

Having thus described my invention, what I claim is—

1. In a non-refillable bottle, the combination with a bottle and its neck, of a sleeve 40 seated within the neck, a valve-body longitudinally slidable within the sleeve and provided with a slot, a valve-head associated with the valve-body, and a weight having a pintle engaging the slot, said weight adapted to draw 45 the valve downward to seat its head upon the sleeve.

2. In a non-refillable bottle, the combination with a bottle and its neck, of a longitudinally-slid valve seated within the neck, 50 a retaining-disk seated above the valve and having corrugated upper and lower faces, and a cup-shaped member seated over the retaining-disk and provided with discharge-openings.

In testimony that I claim the foregoing as my own I have hereto affixed my signature in the presence of two witnesses.

CHARLES A. LINDSTROM.
